CLAIM

The ornamental design for a hand mixer, as shown and described.

DESCRIPTION

FIG. 1 is a top, left and front perspective view of a hand mixer showing the new design;

FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view thereof.

The broken lines shown in the drawings depict portions of the hand mixer that form no part of the claimed design.
